UNITED STATES PATENT OFFICE

2,603,317

BUILDING STRUCTURE

Lyman C. Riggle, Chicago, Ill.

Application July 9, 1946, Serial No. 682,406

4 Claims. (Cl. 189—1)

1

This invention relates to a building structure utilizing novel bimetallic supporting columns.

All exposed structures other than heated buildings are subject to considerable changes in dimensions of the elements of the structure with variations in temperature, resulting in severe temperature stresses, especially in the supporting columns. Examples of such structures are elevated highways, unheated mill buildings and athletic stadia.

Heretofore, several methods of reducing these thermally created temperature stresses have been utilized but have not been completely satisfactory. For example, expansion joints have been included at intervals of 100 to 125 feet in the structure. Such joints are expensive, troublesome, and invariably leak. In elevated highways these expansion joints are bumpy and their maintenance is a source of constant expense. Furthermore, the temperature stresses on the columns require a heavier column section than would otherwise be required. The bending moments induced in the columns by temperature changes cause an eccentricity of load on the footing, as the changes in length of horizontal girders displace the tops of the columns from their normal position directly above the bases of the columns, thus necessitating an increase in footing size and an increase in the number of piles in pile footings.

In solving the difficulties set forth above, I have not attempted to eliminate bending of the column but I have eliminated the temperature stresses in the columns by providing a building structure utilizing novel bimetallic columns. These columns take advantage of the difference in the thermal co-efficients of expansion of two dissimilar materials so that the column automatically curves itself to accommodate itself to the movements of the top of the column due to changes in temperature.

It is a primary object of my invention to eliminate temperature stresses on the upright columns of metallic building structures.

Another object of my invention is to provide a novel structural element which automatically accommodates itself to changes in temperature.

Another object of my invention is to provide a building structure utilizing a structural element which automatically accommodates itself to changes in temperature.

A further object of my invention is to provide a temperature compensating column which is relatively inexpensive to manufacture and which is completely automatic in operation.

Still another object of my invention is to provide a method of eliminating temperature stresses in metal building structures.

These and other objects of the invention will

2

be apparent from the following specification and the accompanying drawings, in which:

Fig. 1 is an elevational view showing one side of a structure utilizing my novel temperature compensating column;

Fig. 2 is an enlarged elevational view of the column positioned furthest from the center column;

Fig. 3 is a transverse elevational view of the column shown in Fig. 2;

Figs. 4 through 7 are cross-sectional views taken on lines 4—4, 5—5, 6—6, and 7—7, respectively, of Fig. 2;

Figs. 8 through 13 are similar to Figs. 2 through 7 but showing the column positioned next inwardly toward the center column from the column shown in Figs. 2 through 7;

Figs. 14 through 20 are similar to Figs. 2 through 7 but showing the column positioned next inwardly toward the central column from the column shown in Figs. 8 through 13; and

Figs. 21 through 23 are diagrams showing the columns shown in Figs. 2 through 7, 8 through 13, and 14 through 20, respectively, after a 60° F. temperature rise above the mean according to an actual example of the structure.

In a preferred embodiment of the invention as shown in the drawings, a structure is shown in Fig. 1 in which a horizontal "I" beam girder 50 is supported by an end column 51 positioned furthest from the center of the structure, column 52 positioned next in order toward the center, then column 53, column 54, and finally center column 55. Similar elements (not shown) are positioned in reverse order on the right side of the center column.

Columns 51 through 53 which are the only ones subject to appreciable deformation during temperature changes are composite columns fabricated of steel and aluminum. Aluminum has approximately twice the coefficient of expansion of steel and this fact is taken advantage of in accomplishing the objects of the invention.

As shown in Fig. 2, column 51 has its upper portion composed of three aluminum plates 56, 57, and 58 on the left side and one steel plate 59 on the right side, the right side being the side toward the center of the structure. In the example shown, plates 56 and 58 are slightly longer than plate 57. Plate 59 is a steel plate of approximately the same length as plate 57. The upper ends of plates 56, 57 and 58 are flush while the lower ends of plates 56 and 58 extend beyond the lower end of plate 57 which is somewhat shorter than plates 56 and 58. Plates 56, 57, and 58 are riveted together by aluminum rivets 60 at the points where the rivets touch only aluminum, while steel rivets are used where the rivets touch steel and aluminum or steel alone.

The center line of the column is considered to be the line midway between the midpoint of the vertical steel plate and the center of the middle aluminum plate.

Plates 58 and 59 are connected by bent steel plates 61 riveted to plates 58 and 59 and spaced an equal distance apart starting from the upper end of the column.

The lower half of the left side of column 51 is comprised of a single steel plate 62 of substantially the same dimensions as plate 59. Plate 62 at its upper end extends into the space between the lower ends of plates 56 and 58 and abuts the lower end of plate 57, three steel rivets 63 being passed through the splice.

On the lower right side of column 51 are three aluminum plates 64, 65 and 66, plates 64 and 66 being of substantially the same dimensions as plates 56 and 58, and plate 65 being of the same dimensions as plate 57. The splice at the point of meeting of plates 64, 65 and 66 with plate 59 is similar to the splice where plate 62 is joined to plates 56 and 58. Bent steel plates 61a are the same as plates 61 but are inverted and are spaced similarly to plates 61 starting from the lower end of the column. The two bent plates 61 and 61a immediately adjacent the center of the column are substantially equidistant from the point where plate 62 abuts plate 57 and plate 59 abuts plate 65.

At the top of column 51, a steel top plate 67 slightly wider than the horizontal I beam 50 is mounted on the end of the column by means of a pair of steel angles 68 each having two bolt holes and riveted one to plates 56, 57, 58 and one to plate 59. Angles 68 are welded to the top plate 67 which has four bolt holes 69 aligned with the bolt holes in angles 68 for bolting the column to "I" beam 50 by bolts 70.

The structure at the base of the column is similar to that at the top with four bolts 72 passing through angles 73 and base plate 74 to anchor the base of the column.

Column 52 is shown in detail in Figs. 8 through 13 and is quite similar to 51 in that it has upper aluminum plates 86, 87 and 88 corresponding to plates 56 through 58 in Fig. 2, and has an upper steel plate 89 corresponding to plate 59 in Fig. 2. Plates 88 and 89 are spaced by U-shaped bent steel plates 90 riveted to the vertical plates 86 through 89 and positioned in pairs facing outwardly along the length of the column.

The lower part of column 52 is generally the same as that of column 51, having a steel plate 92 on the left side, the upper end of which is spliced between the lower ends of aluminum plates by rivets 93. On the right side of the column, three aluminum plates 94, 95 and 96 are spliced to upper steel plate 89 in the same manner that plates 86, 87 and 88 are spliced to plate 92.

The construction at the top and bottom of column 52 is generally the same as in column 51, there being at the top a horizontal steel plate 97 welded to steel angles 98 which are riveted to the upright elements. Bolts 100 pass through the horizontal I beam, through plate 97 and through angles 98. At the base of the column, anchor bolts 102 pass through angles 103 and base plate 104 to anchor the column to the footing (not shown). Angles 103 are riveted to the upright elements and are welded to the base plate.

It will be apparent from the above description that column 52 is quite similar to column 51. However, the upright plates of column 52 are slightly heavier than those of column 51 and the 75

top and bottom horizontal plates are slightly larger. The spacing between each steel plate and the three parallel aluminum plates is greater in column 52.

Column 53 as shown in general in Fig. 1 and in detail in Figs. 14 through 20 is quite different from columns 51 and 52 in the relative lengths of the aluminum plates and the steel plates. The three upper aluminum plates 116, 117, and 118 extend only roughly a fourth of the length of the column while steel plate 119 extends roughly three-fourths of the length of the column. The same is true of lower aluminum plates 124, 125 and 126 and lower steel plate 122. U-shaped bent steel plates 121 and 121a separate the steel plates from the aluminum. The top of column 53 is similar to columns 51 and 52 and has top plate 127, upper angles 128 and bolts 130. The bottom is also similar to columns 51 and 52 and has bolts 132, angles 133 and a base plate 134.

The width and thickness of the plates of column 53 are about the same as those of column 52 and the spacing between plates is about the same. It will be noted that U-shaped plates 121a which contact both steel and aluminum are spaced further apart than plates 121 which contact only steel.

The differences in the dimensions of the various columns is due to the differences in load which they support and to the fact that the upper ends of the columns farthest from the center of the structure must move more than the upper ends of columns nearer to the center.

Columns 54 and 55 as shown in Fig. 1 are conveniently comprised of conventional steel columns. Column 55, being the center column, would not need to be a temperature compensating column. Column 54 is so near to the center that the movement of its upper end due to changes in the length of horizontal girder 50 with changes in temperature would probably be too small to warrant the design and manufacture of a temperature compensating column similar to columns 51, 52, and 53. It is sufficient for column 54 to be designed to take the temperature stresses according to conventional means known to anyone skilled in the art. Of course a temperature compensating column could be used for column 54, if desired.

In an actual example of this structure, columns 51 through 55 were spaced fifty feet apart so that column 51 is 200 feet from the center column 55 of the structure, column 52 is 150 feet from the center, column 53 is 100 feet from the center, and column 54 is 50 feet from the center. All of the columns are 20 feet high.

In this sample structure, the following dimensions were found desirable:

Column 51

Part	Dimension
Plates 56, 58, 64 and 66	10" x $\frac{5}{8}$ " x 10'-3"
Plates 57 and 65	10" x $\frac{5}{8}$ " x 9'-11"
Plates 59 and 62	10" x $\frac{5}{8}$ " x 9'-11"
Distance between plates 58 and 59	4 $\frac{3}{4}$ "
Distance from centerline of plate 57 to centerline of plate 59	6"
Bent plates 61	3" x 4 $\frac{3}{4}$ " x $\frac{1}{2}$ " x 10". 7"
Distance from point of abutment of plates 57 and 62 to adjacent plates 61	1'-6"
Distance between other plates 61	4" x 4" x $\frac{5}{8}$ " x 1'-6". 18" x 1" x 18".
Angles 63 and 73	1 $\frac{1}{2}$ " diameter.
Plates 67 and 74	1 $\frac{1}{2}$ " diameter.
Holes for bolts 70	1 $\frac{1}{2}$ " diameter.
Holes for bolts 72	1 $\frac{1}{2}$ " diameter.
Bolts 70 and 72	1" diameter.

Column 52

Part	Dimension
Plates 86, 88, 94 and 96	12" x $\frac{1}{8}$ " x 10'-6"
Plates 87 and 95	12" x $\frac{1}{8}$ " x 9'-11"
Plates 89 and 92	12" x $\frac{1}{8}$ " x 9'-11"
Distance between plates 88 and 89	6 $\frac{1}{4}$ "
Distance from centerline of plate 87 to centerline of plate 89	8"
Bent plates 90	3" x 6 $\frac{1}{4}$ " x 5"
Distance from point of abutment of plates 87 and 92 to centers of adjacent plates 90	11 $\frac{1}{2}$ "
Distance between other plates 90	1'-11"
Angles 98	8" x $\frac{1}{4}$ " x $\frac{3}{8}$ " x 1'-6"
Angles 103	8" x 6" x $\frac{3}{8}$ " x 1'-6"
Plate 97	18" x 1" x 1'-8"
Plate 104	18" x 1" x 2"
Holes for bolts 100	1 $\frac{1}{8}$ " diameter
Holes for bolts 102	1 $\frac{1}{4}$ " diameter
Bolts 100 and 102	1 $\frac{1}{4}$ " diameter

Column 53

Part	Dimension
Plates 116, 118, 124, 126	12" x $\frac{1}{8}$ " x 4'-6"
Plates 117 and 125	12" x $\frac{1}{8}$ " x 3'-11"
Plates 119 and 122	12" x $\frac{1}{8}$ " x 15'-11"
Distance between plates 118 and 119	6 $\frac{1}{4}$ "
Distance from centerline of plate 117 to centerline of plate 119	8"
Bent plates 121	3" x 7 $\frac{1}{2}$ " x $\frac{1}{2}$ " x 5"
Distance between centers of plates 121a	1'-10 $\frac{1}{2}$ "
Distance between centers of plates 121	1'-6 $\frac{1}{2}$ "
Angles 128	8" x $\frac{1}{4}$ " x $\frac{3}{8}$ " x 1'-6"
Angles 133	8" x 6" x $\frac{3}{8}$ " x 1'-6"
Plate 127	18" x 1" x 1'-8"
Plate 134	18" x 1" x 2"
Holes for bolts 130	1 $\frac{1}{8}$ " diameter
Holes for bolts 132	1 $\frac{1}{4}$ " diameter
Bolts 130 and 132	1 $\frac{1}{4}$ " diameter

In this structure, all rivets touching aluminum only are $\frac{3}{4}$ " diameter aluminum rivets. All other rivets are $\frac{3}{4}$ " diameter steel rivets.

In a structure built according to the measurements set forth above, the diagrams shown in Figs. 21 through 23 illustrate the deformation of columns 51, 52 and 53, respectively for a 60° F. temperature rise. These diagrams assume a mean temperature of 60° F. for a structure used near the 40th parallel of latitude and a temperature change of 60° F. above and below the mean is usually provided for.

As shown in Figs. 21 through 23, for a 60° F. rise in temperature above the mean, the upper end of column 51 deviates .078" from the normal position, the upper end of column 52 moves .058", and the upper end of column 53 moves .039".

In this example, the following design data were used:

	Column 51	Column 52	Column 53
Direct load	.lbs.		
Moment due to .078" eccentricity	inch lbs.		
Steel stress	p. s. i.		
Aluminum stress ¹	p. s. i.		

Mod. of elasticity of steel, 30,000,000 #/in.²

Mod. of elasticity of aluminum, 10,000,000 #/in.²

Coefficient of expansion of steel taken as .0000065.

Coefficient of expansion of aluminum taken as .000013.

¹ Figures contain 900 #/in.² temperature stress.

The design of temperature compensating columns to fit various structural needs can be accomplished in the following manner: Knowing the material of the horizontal girders and their lengths, it is a simple matter by utilizing the coefficient of expansion of the girder material to calculate the amount of movement of the upper end of a column which will be necessary for a column a given distance from the center of the structure.

Let "E" represent the required movement at the top of the column. Then E/2 is the required movement at the center point of the column. Let "R" represent the radius of curvature of each end portion of the column. (In Fig. 21, R=1282'.) Where "L" equals one-half the length of the column, R may be calculated from the formula

$$R = \frac{L^2}{E} + 4$$

We now have the radius "R" required to give the movement "E" at the top of the column.

Let "S" equal the lengthening of the aluminum side of the column due to the greater expansion of the aluminum. Then "L+S" equals the expanded length of the aluminum side of the column, looking at either the upper or lower part of the column. Then to find the depth "D" of the column required to give the desired movement "E" at the top of the column, the following formula is used:

$$D = \frac{RS}{L}$$

The depth "D" is taken as the distance between the centerline of the center aluminum plate and the centerline of the steel plate on the other side of the column. For example, in column 52, the distance "D" is the distance between the centerlines of plates 87 and 89.

An important result of this invention will be the increased use of aluminum in the structural field. Aluminum, desirable because of its light weight, has been difficult to use because of its large coefficient of expansion, but can now be used to a much greater extent in unheated metal building structures. In steel structures, expansion joints may be entirely dispensed with or, if used, can be spaced 400 to 500 feet apart.

While I have described my invention with reference to a presently preferred embodiment thereof, I am aware of the fact that certain changes may be made in the device herein shown and described without departing from the spirit and full intended scope of my invention as defined by the appended claims.

I claim:

1. A structure having at least one elongated structural element of a material which expands and contracts due to temperature changes and at least one column secured at one end to said structural element at an angle with respect thereto, the other end of said column being fixedly mounted to datum, said column comprising two constituent connected members located on opposite sides of the center line of the column, said members being spaced longitudinally along said element but in adjacent parallel relationship to each other, the one of said members facing in the direction of expansion of said element having a coefficient of thermal expansion less than the other of said members, whereby said column will flex laterally to compensate for expansion or contraction in the length of said structural element caused by temperature changes.

2. A structure having at least one elongated structural element of a material which expands and contracts due to temperature changes and at least one column secured at one end to said structural element at an angle with respect thereto, the other end of said column being fixedly mounted to datum, said column comprising two constituent connected members located on opposite sides of the center line of the column, in spaced but adjacent parallel relationship to each

other, one of said members having a coefficient of thermal expansion less than the other of said members, and located on the side of said column facing the direction in which said structural element expands with increases in temperature, whereby said column will flex laterally to compensate for expansion or contraction in the length of said structural element caused by temperature changes.

3. A structure having at least one elongated structural element of a material which expands and contracts due to temperature changes and at least one column secured at one end to said structural element at an angle with respect thereto, the other end of said column being fixedly mounted to datum, said column comprising an upper section consisting of a first member made of a first material and disposed on one side of the centerline of the column and a second member made of a second material having a greater coefficient of thermal expansion than said first material and disposed on the opposite side of the centerline of the column from said first member, said second member facing the direction in which said structural element expands, and a lower section consisting of a third member made of said second material and a fourth member made of said first material, said members comprising said lower section being disposed on opposite sides of the centerline of the column with said third

5 member on the same side as said first member and with said fourth member on the same side as said second member, whereby said column will flex laterally to compensate for expansion or contraction in the length of said structural element caused by temperature changes.

4. A structure according to claim 3 wherein the structure includes a plurality of columns spaced along said structural element, the column nearest the end of said element having the greatest lateral flexural movement and the additional columns having progressively less lateral flexural movement as they are spaced inwardly from the outermost column.
